APPARATUS FOR FILLING METAL CONTAINERS

John F. Werder, Lakewood, Ohio, assignor of one-half to Edmund Rogers, South Euclid, Ohio

Application February 28, 1931, Serial No. 519,133

6 Claims. (Cl. 226—27)

This invention relates to an improved method and apparatus for filling containers with fluids under pressure.

The present form of invention as herein disclosed, is especially adapted for use in the filling of sheet metal containers of the lighter grade, such as tin plate, with a gas-charged lubricant which is capable of discharging itself from the container under its own pressure for the purpose of lubricating automobiles. The present form of filling apparatus is especially adapted for use in connection with the comparatively smaller size containers although it is to be understood that the same principle herein involved may be adopted in the filling of containers which are formed of any material and of any desired size. Also, it is to be understood that such containers may be filled with any fluid under pressure whether of gas or liquid form. The present disclosure is merely for purposes of illustration and there may be devised various modifications without departing from the spirit of the present invention as herein set forth and claimed.

Fig. 1 is a partial plan view of the present form of apparatus; Fig. 2 is a front elevation of one of the containers in filling position; Fig. 3 is a side view of the same; Fig. 4 is a plan view of the connecting means between the container and the filling apparatus, and Fig. 5 shows the valve.

The sheet metal container herein disclosed comprises the cylindrical body 1 and the bulged heads 2 and 3 which have been given such form by means of internal air pressure which is known as the "blowing" process, and which is performed preparatory to the filling of the containers with the gas-charged liquid. The purpose of the "blowing" process is to give to the container as nearly as possible the form which it would naturally assume under the force of the internal pressure to which they are to be subjected when filled. In this way, there may be precluded the danger of the seams breaking under the internal pressure of the gas-charged liquid and the consequent leaking of the same. This process is more fully set forth in my United States patent, Serial No. 1,762,903, June 10, 1930.

In this form of container just referred to, one of the heads is provided with a valve connection through which the same may be filled and later discharged. This valve connection comprises a valve casing, a longitudinally extending opening therethrough, and a lateral discharge port. A screw-threaded valve member which is applied to the longitudinal opening, is adapted to control the

discharge port and may be employed for closing the container when filled to the proper degree and may be employed also in the later control of the discharge through the nozzle.

The filling apparatus comprises means whereby any desired number of containers may be mounted for filling simultaneously. In the present instance, there are disclosed two oppositely disposed racks 8 which have transversely extending openings 9 therethrough at suitable intervals for the connection of the source of supply at one end thereof and the application of the container at the other end thereof. Each container is mounted in inverted position and the tapered end portions 6^a of the discharge nozzle is applied to the squared edge at the one end of the opening 9 so as to afford filling communication with the inside of the container.

The container is maintained in such inverted position by means of an especially constructed holding device which comprises the parallel arms 10 extending through the rack 8 for slidably engagement therewith, these arms being formed as parts of an integral rod or wire which has the intermediate loop portion 11 and the restricted portions 12. The loop portion 11 serves as a means of gripping this device so as to withdraw or open the same against the tension of the springs 13 which surround the parallel arms 10. These springs at one end engage against the disks provided upon the ends of the parallel arms 10 and abut at the other end against the racks 8. The space between the restricted portions 12 and the other side of the rack 8, in each case, is sufficient to accommodate the valve casing of the container so that upon withdrawing the holding device, the container may be placed in such position and will be so held by the engagement of the restricted portions 12 upon releasing the holding device. This manner of holding the container in such position is illustrated in Fig. 4. Since the racks 8 and the nozzles 6 are formed of metal, there is obtained a metal-to-metal contact between the nozzle and the rack as part of the filling connection with the source of supply. By the employment of semi-soft metal in either the nozzle 6 or the rack 8, or in both of them, there may be insured an efficient and dependable seating engagement between the tapered surface 6^a of the nozzle and the squared edge of the annular opening which is engaged by the nozzle at the one end of the passage 9. Such means of filling connection will serve to reduce to a minimum any leaking of the fluid at this point during the filling operation.

At the other end of the passage 9, there is pro-

vided an enlarged screw-threaded seat for engagement by the threaded end portion 14 of the connecting member 15 on the one end of the filling tube 16. The tubes 16 may be more or less flexible and are all connected at their other ends to the distributor 17 which in turn communicates with the pipe 18 from the source of supply. The pressure gauge 19 may be inserted in such supply pipe line.

10 After the gas-charged lubricant is supplied through the connections above described, to the plurality of containers mounted upon the rack or racks, it will be necessary to release a portion of the gas pressure from the containers so as to 15 permit further admission of the liquid to the same, which would otherwise be prevented by the gas pressure within the containers. This step of partially relieving the compression of gas within the containers is known as "sniffing" and for this 20 purpose, there is provided the valve 20 which, when set in one position, affords communication directly through the pipe line 18 from the source of supply to the distributor 17 and thence to the containers. The valve 20 may also be set in another position by means of the handle 21 so as 25 to close temporarily the supply of gas-charged liquid from the pipe line 18 and to permit such release from the containers out through the tube 16, the distributor 17, and the discharge pipe 22.

30 Upon completion of such "sniffing", the valve 20 is returned to filling position to permit further charging of the containers from the source of supply. In this way, there may be stored within the containers a proper degree of free gas under 35 desired pressure so as to insure proper discharge of the liquid from the container and with sufficient gas pressure for completely emptying the same. It is to be understood that allowance is to be made for the fact that during the discharge 40 under such internal pressure, there will be liberation of the gas which will then serve as free gas under increased pressure to assist in the complete discharge of the contents of the container.

45 When the containers have been filled to the proper degree, the valves 7 will be closed so as to prevent escape of the contents from the container upon release of the same from the filling rack. The connection to the source of supply has already been cut off by means of the valve 20 and the 50 containers may then be removed for replacement by other containers to be filled in the same manner. The containers after filling in the manner described, are ready for delivery and the contents thereof may be discharged by opening the valve 7 which permits such discharge through the nozzle 6.

60 In the present form of apparatus in which tubes 16 are all connected to the same distributor 17, and are controlled by the same valve 19 during the "sniffing" process, these tubes 16 are all of the same length regardless of the position of the containers upon the rack, this provision being for the purpose of insuring the same degree of "sniffing" for all containers and the charging of all of them to the same degree. In this way, there is insured a uniform filling of the containers and under the same degree of internal pressure.

65 After the cans have been filled in the manner above described and removed from the filling apparatus, they can be weighed upon conveniently located scales in order to verify the quantity of the contents thereof before preparation for shipment.

70 Whereas it is ordinarily practically impossible to fill a metal container with a liquid under pres-

sure with any degree of certainty or uniformity as to quantity, because of the opaque nature of the metal body, this is readily accomplished by the present method and apparatus.

75 Thus, I have devised a convenient and efficient form of apparatus for simultaneously charging a plurality of containers with a gas-charged liquid under proper degree of pressure for completely emptying the contents of the containers at the time of use. These containers are provided with dependable filling connections during the filling operation and may readily be applied to and removed from the filling apparatus.

10 What I claim is:

1. Apparatus for filling a plurality of metal 15 containers with gas-charged liquid, comprising means for supplying the gas-charged liquid, means for attaching readily removable connecting means of substantially the same length between said supply means and the individual containers, means for indicating the pressure supplied to the containers, and a single means for relieving the interior of the containers from being gas-locked against further filling, whereby the containers may all be filled uniformly to the 20 point desired.

2. Apparatus for filling a plurality of metal 25 containers with gas-charged liquid, comprising means for supplying the gas-charged liquid, a stationary rack to which the containers are applied for supporting the same in inverted position; readily detachable individual connecting means on the rack for establishing communication between said supply means and the containers while supported in inverted position, 30 means for indicating the pressure supplied to the containers, and a single means for controlling the admission of the gas-charged fluid to the containers and for relieving the interior of the containers from being gas-locked against further filling, whereby the containers may all be 35 filled to the point desired.

3. Apparatus for filling a metal container with 40 gas-charged liquid, comprising means for supplying the gas-charged liquid, a stationary support having a port therethrough for receiving the nozzle of a container at one end thereof and having communication at its other end with said supply means, and unitary means for simultaneously supporting the container and releasably clamping the nozzle of the container at two circumferentially spaced points thereof for holding the same in filling engagement with said port.

4. The combination of an apparatus for supplying gas-charged liquid, a container and means 45 for connecting said container to said apparatus, said connecting means comprising a metal member on said supply means and a metal valve body member provided upon the container, said members having line contact with each other and at 50 least one of them being of semi-soft metal, whereby said supply means may be connected directly to said valve body with sealing engagement and the valve body closed upon completion of the filling operation.

5. The combination of an apparatus for supplying gas-charged liquid, a container and a stationary support having a readily detachable means for connecting said container to said apparatus, a valve body on the top end of the container and a tube extending therefrom to the inside bottom region of the container, said valve body being adapted to engage said support so as to support the container in inverted position and to cooperate with said connecting means, and a 70 75

valve-controlled means for relieving the pressure in the container out through said tube during the filling operation so as to permit filling of the liquid into the container to the point desired.

5 6. Apparatus for filling a metal container with gas-charged liquid, comprising means for supplying the gas-charged liquid, a stationary support for the container in inverted position, and said support being provided with a readily detachable and laterally engaging connecting means 10 between said supply means and a valve body on the one end of the container, said connecting means having two-point engagement with said

valve body, said valve body having a side port adapted for direct metal-to-metal communication with said supply means and a valve in said valve body for controlling the flow through said port, and the point of engagement of the valve body with the supply means being equi-distant from the points of engagement between the connecting means and valve body, whereby the container can be maintained in inverted position during the filling operation and said valve may 15 be closed upon completion of the filling operation.
